UNITED STATES PATENT OFFICE.

FRANK H. STOLP, OF GENEVA, NEW YORK.

METHOD OF FORMING SHEET METAL.

1,408,232.

Specification of Letters Patent. Patented Feb. 28, 1922.

Original application filed May 12, 1917, Serial No. 168,260. Divided and this application filed April 9, 1918. Serial No. 227,458.

To all whom it may concern:

Be it known that I, FRANK H. STOLP, of Geneva, in the county of Ontario and State of New York, have invented certain new and useful Improvements in Methods of Forming Sheet Metal; and I do hereby declare the following to be a full, clear, and exact description of the same, reference being had to the accompanying drawings, forming a part of this specification, and to the reference-numerals marked thereon.

My present invention relates to metal working and more particularly to the forming of sheet metal into tubes, moldings and the like, involving the bending or creasing of opposite lateral edges of a strip or blank and the invention has for its object to provide an improved method of this nature whereby a superior product of uniform quality and proportions, free from malformations, may be produced rapidly and without distorting or straining the material worked upon. This application is a division of my prior application Serial No. 168,260, filed May 12, 1917 in which I claim an invention relating to machines through the medium of which this method of invention may be practiced and in describing the latter herein, I have found it convenient to illustrate and describe the machine disclosed in said parent application as giving a clear idea of the mode of treating the material and of the results accomplished. To these and other ends the invention resides in certain improvements and combinations of parts all as will be hereinafter more fully described, the novel features being pointed out in the claims at the end of the specification.

In the drawings:

Figure 1 is a side elevation of the machine;

Figure 2 is a top plan view of the machine;

Figure 3 is a horizontal sectional view of the machine the section being taken on the line 3^x—3^x of Figure 1;

Figure 4 is a vertical cross section through the guide channel for guiding the mandrel of the machine, the section being taken on the line 4^x—4^x of Figure 1;

Figure 5 is a side elevation of the outer end of the mandrel;

Figure 6 is a vertical longitudinal section

through the initial breaking die and folding plunger therefor, the section being taken on the line 6^x—6^x of Figure 3;

Figure 7 is a vertical cross section through the breaking die and folding plunger, the section being taken on the line 7^x—7^x of Figures 3 and 6.

Figures 8, 9, 10 and 11 are vertical cross sections through different sections of the finishing dies for lock seaming the tube, the sections being taken on the line 8^x—8^x, 9^x—9^x, 10^x—10^x and 11^x—11^x respectively of Figure 3.

Similar reference numerals throughout the several views indicate the same parts.

The machine illustrated is designed for the production of lock seam tubing and the present invention will be described for convenience in connection with such an operation, though it will be understood and readily observed by those skilled in the art that other tubing, moldings and the like may be produced in a similar manner.

The methods of making tubing hitherto practiced have usually involved a pull or draw on the metal which tends to make it porous and spongy and with little life left in it. Also, it has been the practice to form the tubing in continuous lengths and to chop, shear or saw it at intervals where a quantity of short tubes is the product sought as, for instance, in the manufacture of automobile radiators and in such a case, the severing operation not only reduces the speed of production but is almost sure to render the ends of the tubes rough or uneven and, generally, imperfect.

My present invention is applicable, particularly as carried out on the machine illustrated, to the production of such short length tubes with great rapidity and with a compressing rather than a stretching effect upon the sheet material used. The ends of the tubes are uniform and true and free from mutilation because identical with the edges of a prepared blank that may be sheared or otherwise formed while in a flat state.

In practicing my invention, I prepare such a blank, usually of rectangular form with squared edges. I then preliminarily bend the blank (which in an automatic machine would be cut and delivered as required from a continuous roll or ribbon) at or near its

center in a manner that maintains its ends parallel and brings its lateral edges parallel and toward each other. While in such condition, I support the inner surfaces of the blank against collapse beyond the inside diametrical limits of the tube desired and support the outside surfaces against expansion beyond the outside diametrical limits of the tube desired. While so held, I form the lateral edges inwardly toward the center with forming dies or otherwise, by an operation conducted progressively toward an end edge of the blank and at the same time, I resist the longitudinal thrust thereby created by pressure against the said end edge. The forming medium may move relatively to the blank while the said end edge rests against a fixed abutment, or a reverse action may be proceeded with whereby the blank is moved by a thrust against its end edge to carry its lateral edges progressively through the point at which the bending or creasing occurs so that, in any event, the strain upon the blank is inwardly from each end in the nature of a compression rather than a tensile strain tending to stretch or disrupt the metal. Being closely supported on both sides, the metal cannot escape submitting to this compression and as a result, the resistance at the creasing point is progressively overcome along its edges. The ends of the tube produced are therefore as perfect as the ends of the prepared blank and the tube is subjected to no lateral strains other than those completely borne by the supporting elements applied to the inner and outer surfaces of the blank. I prefer, where practicable, to push the supported blank endwise past the creasing point.

40 The machine shown in the accompanying drawings for constructing tubing in accordance with the above method will give a better understanding of the invention and its benefits. Referring to the drawing, it comprises a bed plate 1 which forms a run way for the cross-head 2 to slide thereon. The bed plate 1 is supported by suitable legs 3 and 3^a as shown in Figures 1 and 2. Bolted to the top of the bed plate at the left hand end thereof is the channel frame 4 which is formed by the upright plates 5 and 6, which plates embrace the breaking and bending dies as hereinafter described.

45 The forming channel 15, into which the sheet metal plate is forced to conform to the outline thereof, comprises the longitudinal bars 7 and 8 with the bar 9 supported between them. All of these bars together with the upright plates 5 and 6 are rigidly held together by suitable bolts and form the channel frame 4 which in turn is fastened to the bed plate 1 as pointed out above.

50 The longitudinal bars 7, 8 and 9 form the sides and bottom of the guide channel 15 into which the sheet metal plate is forced verti-

cally by means of a plunger to form the bottom and sides of the tube. After this operation is completed, the sheet metal channel formed in this manner is pushed forward by means of a mandrel. On its forward movement with this mandrel, the sides of the sheet metal channel are folded over the top of the mandrel and the ends thereof are gradually locked into each other by means of suitable folding dies until at the end of the forward movement of the mandrel the sheet metal channel has been completely closed at the top with a lock seam so that when the mandrel is withdrawn from the inside thereof, the complete metal tube may be taken off at the end of the machine.

To perform these operations, the different parts of the machine and their cooperation is as follows:

Each of the longitudinal bars 7 and 8 is provided with an angular projection 10 and 11 respectively. These projections extend upwardly between the upright plates 5 and 6 and form supports on each side of the guide channel 15 on top of which the sheet metal blanks are placed as shown at 12 in Figures 6 and 7.

Mounted to slide between the projections 10 and 11 is the plunger plate 13 which is carried on the outer end of the arm 14. This arm is mounted to swing in the channel frame 4 and is pivotally mounted at the upper left-hand corner thereof as shown in Figures 1 and 2. When the plunger 13 is swung from the dotted line position shown in Figure 1 to the full line position shown in the same figure, the sheet metal plate 12, placed on top of the supports 10 and 11, as shown in Figure 6, is bent in the middle thereof and forced down between the projections 10 and 11 and into the guide channel 15 as shown in full lines in Figure 7. The outline of the lower edge of the plunger 13 conforms to the outline of the bottom of the guide channel 15 formed by the bar 9 so that the sheet metal plate 12 forced into this guide channel is bent into a channel having the same outline at the bottom thereof.

The sheet metal channel formed in this manner snugly adheres to the bottom and sides of the guide channel 15 due to the spring action of the sheet metal. This allows the plunger 13 to be withdrawn from the inside of the channel formed thereby leaving the sheet metal channel in place in the guide channel 15. To withdraw the plunger plate 13 from within the channel, the arm 14 is swung back from the full line position to the dotted line position shown in Figure 1.

The reduced outer end 16 of the mandrel 17 is then gradually inserted into the sheet metal tube formed by the plunger 13. This mandrel is supported at the right-hand end thereof by a lug 18 having an opening 130

through the center thereof through which the end of the mandrel 17 passes. Lock nuts 19 and 20 are provided on each side of the lug 18 and are threaded on the end of the 5 mandrel 17 by means of which this end of the mandrel can be rigidly fastened to the lug 18 as shown in Figures 1 and 2. The lug 18 is carried on top of the cross-head and forms a part thereof.

10 To move the forward end 16 and the mandrel 17 into the sheet metal channel previously formed by the plunger 13, the cross-head 2 is moved to the left on the bedplate 1.

15 As previously described, the outer end 16 of the mandrel 17 is of reduced diameter and is formed out of an upper section 21 and a lower section 22. The dividing line between these sections tapers towards the outer end of the mandrel so that the lower section 22, 20 which is shorter than the upper section 21, can slide in and out thereon, it being understood that the upper section 21 is integral with the mandrel 17 while the lower section 22 is made a separate member thereof. This 25 is for a purpose that will presently appear.

30 The shoulder 23 formed on the inner end of the reduced end 16 of the mandrel 17 is adapted to engage the outer edge of the sheet metal channel on the forward movement.

35 The outside diameter of the reduced end 16 equals the inside diameter of the sheet metal channel, while the outside diameter of the remainder of the mandrel 17 equals the outside diameter of the sheet metal channel, 40 which in turn equals the inside diameter of the guide channel 15. From this it will be seen that when the outer end of the mandrel has engaged the inside of the sheet metal channel, the sides of the mandrel beginning with the shoulder 23, form a continuation 45 of the sides of the sheet metal channel and completely fill the inside of the guide channel 15.

50 During the forward movement of the mandrel the sheet metal channel remains stationary in the guide channel 15 until the shoulder 23 engages the right-hand end of the sheet metal channel. In order to prevent any accidental forward movement of the sheet metal channel before the outer section 16 of the mandrel has completely filled the inside thereof and before the shoulder 23 has come in contact therewith a latch 24 is provided which projects into the inside of 55 the channel frame 4 and across the path of the upper edge of the sheet metal channel as shown in Figure 7. This latch prevents the forward end of the sheet metal channel to move in the guide channel 15 beyond the 60 projections 10 and 11 until the opposite end thereof has been engaged by the shoulder 23 of the mandrel 17. When the shoulder 23 has engaged the sheet metal channel on the forward movement of the mandrel, the latch 65 24 is lifted to allow the mandrel 16 to carry

the sheet metal channel with it and force it between the finishing dies as will presently appear.

65 Mounted on top of the longitudinal bars 7 and 8 and overlapping the guide channel 15 are suitable finishing dies which gradually bend the upper portions of the sides of the sheet metal channel toward each other and also lock the ends thereof together to convert the sheet metal channel into a tube. 70 These finishing dies comprise several members which are illustrated in Figures 3, 8, 9, 10 and 11.

75 The member 25 which is mounted on top of the bar 7 partially overlaps the guide 80 channel 15 and is shaped on the under side thereof to bend the upper portion of the right-hand side of the sheet metal channel towards the left and over the top of the mandrel 16. The outer edge of this same 85 side of the sheet metal channel is then bent back over the top of the member 25 by means of the member 26 as shown in Figure 8. At the same time the upper portion of the left-hand side of the sheet metal channel is bent 90 towards the right and over the top of the mandrel 16 by means of the member 27 which member is mounted on top of the bar 8 and overlaps the guide channel 15 from the left. 95

100 The member 28 carried on the outside of the member 27 then gradually bends the outer edge of the left-hand side of the sheet metal channel over the edge of the outer end of the right-hand side of the sheet metal channel until the outer end of the left-hand side of the sheet metal channel completely embraces the extreme outer end of the right hand side of the sheet metal channel as shown in Figures 9 and 10. 105

110 After successively passing each of these members the finishing member 29 forces the joint thus made by the previous members down upon the top of the tube and partially into the groove 31 formed in the top of the upper section 21 of the mandrel 16.

115 The mandrel and sheet metal tube emerges, after passing underneath all of these members, from the left-hand side of the machine and moves out thereof until the whole of the sheet metal channel is formed into a tube. It will be understood that during the forward movement of the mandrel 16 the upper section 21 thereof has moved over the top of the lower section 22 until the diameter of the combined mandrel was large enough to completely fill out the inside of the tube which is gradually formed thereon, and when the mandrel 16 is withdrawn, the tube formed thereon is released therefrom as follows: 120

125 The upper section 21 on its rearward travel slides over the lower section 22 thereof until the pin 30 comes in contact therewith. This movement of the upper section 22 over 130

the lower section 21 reduces the diameter of the mandrel 16 because of the inclined surface of each of the sections. The reduction of the diameter of the mandrel in turn releases the inside of the finished tube from the mandrel 16 and allows it to be taken off therefrom. After the tube is released from the mandrel the pin 30 carries the lower section 22 with the upper section 21 to the rear and brings it into position for the forming of a new tube.

While the drawings show this machine adapted to form a hexagonal metal tube, it is understood that any other form such as a round or oval tube may be formed with the same machine by simply changing the outline of the bottom of the guide channel and using a mandrel having a cross section corresponding to the outline of the tube to be formed thereon.

I claim as my invention:

1. A method of forming tubing which consists in bending a sheet metal blank to bring its lateral edges into closer proximity, supporting its inner surfaces against collapse

beyond the inside diametrical limits of the tube desired, supporting the outside surfaces of the blank against expansion beyond the outside diametrical limits of the tube desired, forming and interlocking the lateral edges of the blank by a longitudinal creasing operation conducted progressively toward an end edge of the blank while the latter is so interiorly and exteriorly supported and opposing the longitudinal strain of the creasing operation by pressure against the said end edge of the blank.

2. A method of forming sheet metal strips which consists in bending the strip transversely to immediately bring its lateral edges into proximity, supporting the inner and outer surfaces of such bent strip in their intended form and ultimate shape with only its lateral edges exposed, forming said edges by a creasing operation conducted progressively toward an end edge of the strip and opposing the longitudinal strain of the creasing operation by pressure against the said end edge of the blank.

FRANK H. STOLP.
